[57] CLAIM

The ornamental design for a safety belt buckle for a
lifeboat chair or the like, substantially as shown.

DESCRIPTION

FIG. 1 is front elevational view of a belt buckle for a
lifeboat chair or the like showing my new design;

FIG. 2 is a front elevational view in unbuckled condition;

FIG. 3 is a rear elevational view thereof; and

FIG. 4 is a bottom plan view thereof.
